CLAIM

I claim the ornamental design for a preamplifier, as shown and described.

DESCRIPTION

FIG. 1 is a perspective view of a preamplifier.

FIG. 2 is a front-side view of the preamplifier of FIG. 1.

FIG. 3 is a top view of the preamplifier of FIG. 1.

FIG. 4 is a back-side view of the preamplifier of FIG. 1.

FIG. 5 is a left-side view of the preamplifier of FIG. 1.

FIG. 6 is a bottom view of the preamplifier of FIG. 1.

FIG. 7 is a right-side view of the preamplifier of FIG. 1; and, FIG. 8 is an environmental view of the preamplifier of FIG. 1. The broken lines consisting of evenly sized short dashes depict parts of the preamplifier that form no part of the claimed design; whereas, the broken lines consisting of long dash and two short dashes define the boundary of the claim, which extends to the boundary but does not include the boundary; and the broken lines in FIG. 8, consisting of a long dash and one short dash, depict environmental subject matter only and form no part of the claimed design.
